EQUALIZER

Paul W. Klipsch, Houston, Tex., assignor to Esme
E. Rosaire, Houston, Tex.

Application March 23, 1939, Serial No. 263,614

9 Claims. (Cl. 178—44)

This invention relates to wave transmission networks, particularly to equalizer networks having adjustable attenuation characteristics.

An object is to provide an adjustable equalizer network having an image impedance which is a constant resistance for all adjustments of equalization and one in which the amount of equalization may readily be adjusted with a minimum number of variables.

Another object is to provide an equalizer with a minimum number of reactive elements and in which the only variable elements are pure resistances.

Another object is to provide an equalizer in which both ends of a frequency spectrum may simultaneously and practically independently be equalized, compensated or predistorted.

A further object is to form a simple equalizer whose complementary circuit is as readily constructed, and such that a given equalizer and its complement may be used for predistortion and restoration with negligible net distortion.

These and other objects will be evident from the specification and illustrations.

Fig. 1 shows a form of a circuit adapted to transmit the low frequencies with less attenuation than the rest of the spectrum.

Fig. 2 shows a family of performance curves for the circuit of Fig. 1 for different amounts of equalization.

Fig. 3 shows a circuit adapted to attenuate the high frequencies less than the remainder of the spectrum.

Fig. 4 shows a circuit for attenuating both the high and low frequencies by adjustable predetermined amounts less than the rest of the spectrum.

Fig. 5 is a graphical illustration of the performance of the circuit of Fig. 4.

Fig. 6 is a circuit which generalizes the invention by the use of but two impedances.

Fig. 7 is the H section equivalent of Fig. 6.

Figs. 8 and 9 are the lattice equivalents of Fig. 6.

Fig. 10 depicts two equalizers used to extend the range of a single one.

Fig. 11 graphically shows the performance of equalizers as depicted in Fig. 10 where each of the equalizers is of the form of Fig. 1, but whose mid-frequencies are not equal.

Fig. 12 shows an alternative form of the invention involving a transformer.

The following list of symbols will be used:

f =frequency.

f_1 =mid-frequency for "low-pass."

f_2 =mid-frequency for "high-pass."

α =attenuation constant at frequency f .

α_1 =attenuation at frequency f_1 .

α_m =maximum attenuation, or base loss due to pad R_{11} , R_{12} .

α_n =minimum attenuation due to pad R_{11} , R_{12} bridged by R_{21} , R_{22} .

β =phase angle of output voltage with respect to input voltage.

10 $\Gamma = \alpha + j\beta$, the transfer constant.

R_o =characteristic (image) impedance.

15 l. r.=linear range, or range of frequencies over which the attenuation varies linearly with the log of the frequency.

X_{mn} =reactance of arm mn .

Z_{mn} =impedance of arm mn .

Fig. 1 shows a form of the invention, an equalizer to boost the low frequencies (hence referred to as a low-pass type) with input terminals 1 and 2 and output terminals 3 and 4. When operated between resistances R_o there are no reflection losses at the terminals.

In Figs. 1, 3, 4, and 6, the resistor combination $\frac{1}{2}R_{11}$, R_{21} constitutes a simple T attenuator. The values of R_{11} and R_{12} are determined from the line impedance and the total loss. Thus

$$30 \quad \frac{1}{2}R_{11} = R_o \tanh \frac{\alpha_m}{2} \quad (1)$$

$$35 \quad R_{21} = R_o \frac{1}{\sinh \alpha_m} \quad (2)$$

where α_m is the maximum loss in nepers due to the unbridged T and R_o is the characteristic impedance.

A convenient table for the determination of R_{11} and R_{21} is to be found in a paper by P. K. McElroy in Proceedings Institute of Radio Engineers, vol. 23, pages 213-233, March 1935. As an example, suppose 10 decibels loss is desired and the pad is to be used between 500 ohm terminations. The base loss or maximum attenuation is

$$40 \quad \alpha_m = \frac{10}{8.68} = 1.15 \text{ nepers}$$

$$45 \quad \frac{1}{2}R_{11} = 500 \tanh 0.575$$

$$50 \quad = 260 \text{ ohms}$$

$$55 \quad R_{21} = 500 \frac{1}{\sinh 1.15} \text{ and}$$

$$= 351 \text{ ohms}$$

The values L_{12} and C_{22} in Fig. 1 are determined from

$$L_{12} = \frac{Ro}{2\pi f_1} \quad (3)$$

$$C_{22} = \frac{1}{2\pi f_1 Ro} \quad (4)$$

where f_1 is the frequency at which approximately half the equalization is attained, and is herein called the mid-frequency.

An alternative to and exact equivalent of the R_{11} , R_{21} T pad is the bridged T shown by McElroy (mentioned above) in his Fig. 5, page 222, and table VII, page 233.

The adjustable resistors R_{12} and R_{22} are related

$$R_{12} \cdot R_{22} = Ro^2 \quad (5)$$

$$\frac{1}{2}R_{12} = Ro \frac{\tanh \frac{1}{2}\alpha_m \cdot \tanh \frac{1}{2}\alpha_n}{\tanh \frac{1}{2}\alpha_m - \tanh \frac{1}{2}\alpha_n} \quad (6)$$

where α_n is the minimum loss in nepers due to the T with R_{12} and R_{22} connected.

The dotted lines in Figs. 1, 3, 4, 6, and 9 indicate that R_{12} and R_{22} are simultaneously variable whereby the relation in Equation 5 is satisfied.

Continuing the example in which $Ro=500$ and $\alpha_m=10$, suppose it is desired to make R_{12} and R_{22} adjustable in a series of steps in which the correction or equalization values are 0, 2.5, 5, 7.5 and 10 decibels. Using Equations 5 and 6 the following values may be found.

Table I

Correction decibels	$\frac{1}{2}\alpha_n$ neper	R_{12}/Ro	R_{12} ohms	R_{22} ohms
0	0.575	∞	∞	0
2.5	0.431	3.72	1,860	135
5.0	0.288	1.21	557	412
7.5	0.144	0.394	197	1,270
10.0	0.0	0.0	0	∞

Since the circuit of Fig. 6 is the generalized circuit of Fig. 1 and since the circuits of Figs. 6 and 8 are equivalent, the total insertion loss is given by the constant R lattice equation

$$\tanh \frac{1}{2}\Gamma = Z_A/Ro \quad (7)$$

where Z_A in Fig. 8 is the impedance of $\frac{1}{2}R_{12}$ in parallel with $\frac{1}{2}Z_{12}$ and $\frac{1}{2}R_{22}$ in series in Fig. 6 and Γ is the transfer constant defining the loss and phase angle. Note that (7) defines both the transfer constant and total insertion loss when there are no reflection losses, that is when the network is operated between terminal impedances equal to Ro .

Using Equation 7, the performance of the circuit of Fig. 1 is computed and shown in Fig. 2, in which curves of loss against reactance are plotted for different values of R_{12} .

Fig. 3 is the high-pass counterpart of the low-pass circuit of Fig. 1. It may be made complementary thereto whereby the sum of the losses of the circuits of Figs. 1 and 3 are substantially constant by proper choice of the value of f_2 , thereby making, in combination with the circuit of Fig. 1, a convenient predistorting-restoring network. Its performance may be found from Fig. 2 simply by using the reciprocal of the abscissa. Equations 1, 2 and 5 to 7 are applicable. Equations 3 and 4 are applicable to Fig. 2 if L_{22} is written for L_{12} and C_{12} for C_{22} .

Obviously more complicated impedances than, for example, L_{12} , C_{22} in Fig. 1 may be used. Resonant and anti-resonant circuits and multiple branch impedances may be employed, and the

simplicity of the variable feature will be retained. Fig. 6 illustrates the invention in this broader form. The design of such impedances may be accomplished by the use of such references as 5 Everitt's "Communication Engineering" McGraw Hill, 1932, 1937, a book, Chapter IX, and the references given therein. Equations 1, 2, and 5 to 7 still apply, and suitable impedance design may be substituted for (3) and (4); see also "A reactance theorem," R. N. Foster, Bell System Technical Journal, vol. III, No. 2, April 1924.

As an example of such an elaboration, suppose 15 Z_{12} is a reactance in the form of an inductance L_{12} in series with a capacitance C_{12} . The resulting 20 performance will be a certain maximum loss with a drop to a smaller loss at a frequency f_1 determined by the product $L_{12} \cdot C_{12}$. The correction at 25 f_1 will be $\alpha_m - \alpha_n$ and the width of the resulting pass band or the stepness of the loss-frequency curve for a given set of values α_m , α_n will be determined by the ratio L_{12}/C_{12} . Still another type of impedance Z_{12} would result from the two terminal impedance of a reactive ladder with resistance or reactance termination. The impedance in such a case would not be a nearly pure reactance, but would contain a larger dissipative elements are used.

Fig. 4 is a combination high-pass and low-pass 30 equalizer by means of which both ends of a spectrum may be boosted relative to the middle somewhat in the same way that the circuits of Figs. 1 and 3 would perform in tandem, but the total base insertion loss is that of a single circuit only. In 35 the case of Fig. 4 however the equalization is accomplished with resonant and anti-resonant circuits whereby the performance curve slopes are made more steep and the losses increase beyond the limits of 50 and 8000 cycles. The high and 40 low ends may be equalized substantially independently if the mid-frequencies f_1 and f_2 are separated a sufficient amount.

Fig. 5 is the performance of the circuit of Fig. 4 45 where the low-pass mid-frequency (f_1) is 50 cycles, the high-pass mid-frequency (f_2) is 8000 cycles, the pad loss, α_m , is 10 decibels, and the values of R_{12} , R_{22} and R_{13} , R_{23} are chosen from Table I.

The numerical values of L_{12} , C_{12} , L_{22} , C_{22} etc. for 50 Fig. 4 may be computed from (3) and (4) and for the example given where $f_1=50$, $f_2=8000$,

$$\sqrt{\frac{L}{C}} = \frac{1}{2}Ro$$

55 and $Ro=500$ ohms they are:

Table II

$$\begin{aligned} L_{12} &= 0.795 \text{ henry} & C_{12} &= 12.57 \mu\text{f.} \\ L_{22} &= 3.18 \text{ henry} & C_{22} &= 3.19 \mu\text{f.} \\ L_{13} &= 0.005 \text{ henry} & C_{13} &= 0.08 \mu\text{f.} \\ L_{23} &= 0.020 \text{ henry} & C_{23} &= 0.02 \mu\text{f.} \end{aligned}$$

And the values of R_{12} , R_{22} and R_{13} , R_{23} are given in Table I.

It should be understood that the numerical 65 values given are not intended to limit the scope of the patent, but to serve as illustrations of computation by means of the various equations given.

Whatever the nature of Z_{12} , it is necessary that 70 Z_{22} be inverse thereto. Thus in order that the network of Fig. 6 have an iterative or image impedance which is a constant resistance it is necessary that Z_{12} and Z_{22} be inverse, that is that they be related by

$$Z_{12} \cdot Z_{22} = Ro^2 \quad (8)$$

It may be noted that in Fig. 1 this requirement is met since

$$j\omega L_{12} \cdot \frac{1}{j\omega C_{22}} = R_0^2$$

Thus the determination of Z_{12} by whatever design procedure is employed is sufficient also to determine Z_{22} . Inverse networks are discussed and the method of their derivation shown by T. E. Shea "Transmission Networks and Wave Filters," van Nostrand, 1929, chapter 5.

Obviously, the circuits of Figs. 1, 3 and 4 may be made into networks which are balanced and symmetrical with respect to ground simply by transforming them into their equivalent lattices or H sections. This procedure is well known (Bartlett, A. C., Phil Mag. 4, pages 902-907, Nov. 1927) for lattices and is obvious for H sections. Fig. 9 shows a lattice which is equivalent to the bridged T of Fig. 6, and Fig. 8 shows the generalization of Fig. 9. Fig. 7 shows the balanced bridged H which is equivalent to the bridged T of Fig. 6. A still further possible equivalent configuration consists in the reduction of the lattice of Fig. 9 or Fig. 8 to a bridged T containing a transformer t as shown in Fig. 12.

Fig. 12 illustrates an equivalent of Fig. 4 when $2Z_A$ is equal to the impedance of terminals 1 and 3 of Fig. 4 (terminals 2 and 4 not being connected) and Z_B is equal to the shunt arm plus $\frac{1}{2}R_{11}$ of Fig. 4. By similar reasoning Fig. 8 is the equivalent of Fig. 4 when Z_A and Z_B have the same meanings as defined above for Fig. 12. Development of Fig. 4 into a balanced H consists simply of creating a mirror image of Fig. 4 below the line between terminals 2, 4 whereby the line between terminals 2, 4 becomes a neutral which may be retained or eliminated as desired.

The circuits shown, when designed according to the equations herewith, are characterized by an image impedance which is a constant resistance at all frequencies so that the real part of the transfer constant is equal to the total insertion loss when a given circuit is operated between terminations having the same image impedance.

Depending upon the degree of linearity demanded, the attenuation of the circuit of Fig. 1 is linear over a range of two or three octaves. By using a plurality of such equalizers with their mid-frequencies $f_{1a}, f_{1b}, \dots$ etc. spaced at two to four octave intervals, the linear range may be extended over any desired frequency range. Fig. 10 shows two units cascaded, and Fig. 11 shows the results of cascading where curve 11 shows the performance of a unit with a mid-frequency f_{1b} greater than f_{1a} by the amount of the linear range, and curve 12 shows the sum of curves 11 and 12 produced by the cascaded units. The linear range 1. r.2 of the combination is roughly twice the value of 1. r.1.

The invention claimed is:

1. A constant resistance variable attenuation equalizer comprising a dissipative T network, two arms comprising reactances X_{12} and X_{13} bridging said T , variable resistances R_{12} and R_{13} in series with said reactances, and two arms comprising reactances X_{22} and X_{23} each in shunt with a variable resistance R_{22} and R_{23} and connected in series with the shunt arm of said T , said reactances and resistances being related substantially

$$R_{12} \cdot R_{22} = R_{13} \cdot R_{23} = X_{12} \cdot X_{22} = X_{13} \cdot X_{23} = R_0^2$$

2. An adjustable attenuation equalizer for independently adjusting the transmission loss over a plurality of ranges within a frequency spectrum, said equalizer comprising a base loss network having a given finite loss and a given image impedance, a plurality of impedances in shunt with each other and with an arm of the base loss network, each of said impedances comprising reactance in series with a variable resistor, a second plurality of impedances in series with each other and with another arm of said base loss network, said second impedances each comprising reactance in parallel with a resistor which is variable in inverse relation to the resistors contained in the first mentioned impedances, said second impedances being inverse to said first impedances, said first and second impedances and said base loss network being arranged to form a lattice and to exhibit a constant image impedance in both directions of transmission for all values of adjustments of the variable resistors.
3. In an equalizer having fixed resistances in a T configuration and having a predetermined finite base loss and image impedance the combination therewith of circuit elements for producing adjustable amounts of attenuation comprising variable resistances bridging the T , other variable resistances in series with the pillar arm of said T , impedances in series with said first variable resistances, other impedances in shunt with said other variable resistances; said impedances being mutually inverse and said variable resistances being mutually inverse for all values.
4. An adjustable attenuation equalizer for independently adjusting the transmission loss over a plurality of ranges within a frequency spectrum, said equalizer comprising a base loss network having a given finite loss and a given image impedance, a plurality of impedances in shunt with each other and with an arm of the base loss network, each of said impedances comprising reactance in series with a variable resistor, a second plurality of impedances in series with each other and with another arm of said base loss network, said second impedances each comprising reactance in parallel with a resistor which is variable in inverse relation to the resistors contained in the first mentioned impedances, said second impedances being inverse to said first impedances, said first and second impedances and said base loss network being arranged to exhibit a constant image impedance in both directions of transmission for all values of adjustments of the variable resistors, said first mentioned plurality of impedances and the arm of the base loss network shunted thereby bridging a unity-ratio series-aiding transformer, and said second plurality of impedances and the arm of the base loss network in series therewith being connected to the mid-point of said transformer to form a pillar arm.
5. An adjustable attenuation equalizer for independently adjusting the transmission loss over a plurality of ranges within a frequency spectrum, said equalizer comprising a base loss network having a given finite loss and a given image impedance, a plurality of impedances in shunt with each other and with an arm of the base loss network, each of said impedances comprising reactance in series with a variable resistor, a second plurality of impedances in series with each other and with another arm of said base loss network, said second impedances each comprising reactance in parallel with a resistor which is

variable in inverse relation to the resistors contained in the first mentioned impedances, said second impedances being inverse to said first impedances, said first and second impedances and said base loss network being arranged to exhibit a constant image impedance in both directions of transmission for all values of adjustments of the variable resistors.

6. An adjustable attenuation equalizer for independently adjusting the transmission loss over a plurality of ranges within a frequency spectrum, said equalizer comprising a base loss network having a given finite loss and a given image impedance, a plurality of impedances in shunt with each other and with an arm of the base network, each of said impedances comprising reactance in series with a variable resistor, a second plurality of impedances in series with each other and with another arm of said base loss network, said second impedances each comprising reactance in parallel with a resistor which is variable in inverse relation to the resistors contained in the first mentioned impedances, said second impedances being inverse to said first impedances, said first and second impedances and said base loss network being arranged to exhibit a constant image impedance in both directions of transmission for all values of adjustments of the variable resistors, said base loss network comprising a T, the first mentioned impedances bridging the T, and the second impedances being in series with the shunt arm of the T.

7. An adjustable attenuation equalizer for independently adjusting the transmission loss over a plurality of ranges within a frequency spectrum, said equalizer comprising a base loss network having a given finite loss and a given image impedance, a plurality of impedances in shunt with each and with an arm of the base loss network, each of said impedances comprising reactance in series with a variable resistor, a sec-

ond plurality of impedances in series with each other and with another arm of said base loss network, said second impedances each comprising reactance in parallel with a resistor which is variable in inverse relation to the resistors contained in the first mentioned impedances, said second impedances being inverse to said first impedances, said first and second impedances and said base loss network being arranged to exhibit a constant image impedance in both directions of transmission for all values of adjustments of the variable resistors, said base loss network having an attenuation between 10 and 20 decibels.

8. A constant resistance variable attenuation equalizer comprising a dissipative T network, two arms each comprising a reactance and a variable resistance in series and each arm bridging said T, and two arms each comprising a reactance and a variable resistance in parallel, said last mentioned arms being connected in series with each other and with the shunt arm of said T, said last mentioned arms being inverse to said first arms with respect to the image impedance of the network so that the product of each second arm with its corresponding first arm is equal to the square of the image impedance of the network.

9. A constant resistance variable attenuation equalizer comprising a dissipative T network, a plurality of arms each comprising a reactance and a variable resistance in series and each of said arms bridging said T, and a plurality of arms each comprising a reactance and a variable resistance in parallel, said last mentioned arms being connected in series with each other and with the shunt arm of said T, said last mentioned arms being inverse to said first arms with respect to the image impedance of the network so that the product of each second arm with a corresponding first arm is equal to the square of the image impedance of the network.

PAUL W. KLIPSCH.
